UNITED STATES PATENT OFFICE.

SAMUEL PRESCOTT BUSH, OF COLUMBUS, OHIO, ASSIGNOR TO THE BUCKEYE
MALLEABLE IRON AND COUPLER COMPANY, OF COLUMBUS, OHIO.

CAR-COUPLING.

SPECIFICATION forming part of Letters Patent No. 734,813, dated July 28, 1903.

Application filed January 22, 1902. Serial No. 90,837. (No model.)

To all whom it may concern:

Be it known that I, SAMUEL PRESCOTT BUSH, of Columbus, in the county of Franklin and State of Ohio, have invented certain new and useful Improvements in Car-Couplings; and I do hereby declare the following to be a full, clear, and exact description of the invention, such as will enable others skilled in the art to which it appertains to make and use the same.

My invention relates to an improvement in car-couplings, the object of the same being to provide improved locking mechanism which when operated will throw open the knuckle, and is designed particularly as an improvement on Patent No. 683,802, granted to James Timms November 5, 1901.

With this object in view the invention consists in certain novel features of construction and combinations and arrangements of parts, as will be more fully hereinafter described, and pointed out in the claim.

In the accompanying drawings, Figure 1 is a side view, partly broken away, illustrating my improvements. Fig. 2 is a top view, partly in section. Fig. 3 is a view illustrating the locking-block removed; and Fig. 4 is a view looking at the rear of the knuckle, showing the locking-block in its locked position.

While my invention relates to the locking mechanism, which when operated will throw open the knuckle, I will briefly describe the complete coupling, so as to enable the construction and operation of the entire device to be clearly understood.

1 represents the coupling-head, to which is pivotally connected the knuckle 2 by a pin 3, and said knuckle 2 being made on its inner end with a tail 5, curved approximately concentric with the axis of the knuckle, and 40 the coupling is made with a hollow enlargement 6 to receive the tail of the knuckle when the latter is closed.

7 represents the angular locking-block which is mounted to move vertically in a chamber 8 in the coupling-head. The locking-block is operated by a chain 9, secured thereto and extended up through an opening 10 in the coupling-head, which opening is located to one side of the center of the block 50 7, so as to give a lateral as well as a vertical pull on the block to tip it to an inclined po-

sition, as will more fully hereinafter appear. A suitable cap or closure 10^a is secured on one of the links of the chain to close the opening 10 when the knuckle is locked and prevent the chain from falling into the coupling-head. The block 7 is chambered, as at 11, to form the shoulder 12, which latter is beveled or undercut, as shown in Fig. 3, to engage the hook or seat 19, secured to or formed integral with the head 1 above the tail of the knuckle, the upper face of the hook or seat 19 being similarly curved or beveled, so as to positively retain the block in its elevated position against accidental displacement. The 65 block is made with a vertical groove 13 to receive a tongue 14 on the knuckle and securely lock the same in the head. The lower portion of the block 7 is cut away or recessed, as at 15, sufficiently to permit the tail of the 70 knuckle to pass freely between a roller 16, mounted in the upper face of the laterally-projecting nose 20, at the lower end of the block, and a shoulder 17, formed by the recess in the block and located about midway 75 between the ends thereof, for a purpose which will more fully hereinafter appear.

When it is desired to open the knuckle, the chain 9 is pulled upward to lift block 7, drawing the grooved portion 13 thereof free 80 from the tongue 14, and when the tail 5 of the knuckle alines with the recessed portion 15 of the block a further upward pull on the chain will draw the roller 16 in an oblique direction against the beveled or inclined 85 lower face of the tail and, owing to the pressure of the roller 16 against the inclined tail of the knuckle, throw the latter to its extreme open position. When the pull on the chain is released, the shoulder 17 will rest on the 90 knuckle-tail and remain thereon until the knuckle is closed, when the block will fall into its locked position above described.

If cars are coupled together and it is desired to unlock the knuckle without opening 95 the same, the block 7 is drawn up far enough to aline the tail of the knuckle with the recessed portion 15 thereon, the chain exerting a lateral as well as a vertical pull on the block, tilting it and pulling the lip 12 over 100 onto the seat 19, secured to or integral with the draw-head, in a position above the tail of

the knuckle, and as the lip 12 and the seat 19 are slightly inclined the block will be retained in this inclined position, and thereby make it difficult to shake or jar it from off its seat.

The upper face of the tail of the knuckle from the tongue 14 rearwardly is approximately flat or horizontal, as shown at 5^a, for the purpose of permitting the knuckle to turn 10 in its opening movement some little distance before engaging the shoulder 17 of the locking-block for dislodging the latter from its set position, and the upper surface of the curved edge of the tail from the point 5^a to 15 its rear end is upwardly inclined to engage the shoulder 17 of the locking-block and disengage it from its seat 19. The upper surface of the tail between the pivot-pin and the outer curved edge is made slightly convex or 20 is inclined upwardly from its curved edge toward the pivot-pin of the knuckle, so as to engage the shoulder 17 near its free edge or its edge adjacent to the tail, and thus cause the locking-block to tip outwardly and carry 25 the lip 12 out of the path of the hook 19, so that in the locking action of the knuckle when the locking-block is supported wholly on the tail of the knuckle the lip 12 descends in a plane outside of the plane of the seat 19, thus permitting the block to fall to its locked 30 position without interference.

The locking-block is, as before stated, chambered to form a beveled shoulder 12, which when the block 7 is raised so that the locking-surface thereof clears that of the knuckle-arm it (the lock) will by reason of the diagonal or oblique movement given it by the chain engage with or rest on the corresponding seat or projection 19 formed on the coupling-head, and thus hold the lock in a suspended position independent of the knuckle-tail when the latter is in its closed or locked position. The locking-block 7 maintains this independent position relative to the knuckle-tail up to a position of the latter between that of fully closed and fully opened.

As the knuckle-tail swings outwardly a point in its movement is reached when it engages the locking-block, and continuing its movement moves the latter up and away from 50 its support, completely disengaging the two, as before explained, and thus carrying the lock on the upper surface of the knuckle-tail and putting it into a position to drop into a locked position when the knuckle-tail shall 55 have been swung to a closed or locked position.

The feature of improvement in the present device over that disclosed in the patent referred to is in the employment of a roller 16 60 on the locking-block instead of the fixed integral lip shown in said patent.

By the use of the roller, the locking-block bearing against the tail of the knuckle, the resistance offered in throwing the knuckle 65 open by the upward movement of the lock is somewhat reduced.

Having fully described my invention, what I claim as new, and desire to secure by Letters Patent, is—

In a car-coupling the combination with a draw-head, and a knuckle pivotally mounted therein, and provided with a rearwardly-projecting tail having an inclined upper face and an inclined lower edge, of a vertically-movable locking-block, a roller mounted in the upper face of the lower member of the block to engage the lower inclined edge of the knuckle-tail, said block provided with a shoulder to be engaged by the inclined upper face of said tail, and means within the draw-head for holding the locking-block out of its locked position, until released by contact with the inclined upper face of the knuckle-tail, substantially as set forth.

In testimony whereof I have signed this specification in the presence of two subscribing witnesses.

SAMUEL PRESCOTT BUSII.
